ASSIGNORS TO CHRYSLER CORPORATION, OF DETROIT, MICHIGAN, A CORPORATION
OF DELAWARE

LAMP AND LAMP MOUNTING

Application filed November 13, 1930. Serial No. 495,461.

This invention relates to an improved lamp and lamp mounting, particularly for instrument boards of vehicles, radios and the like.

The main objects of the invention are to provide means for securing a lamp of this kind to a support; to provide integral bayonet joint elements on a lamp mounting which are adapted to secure the lamp to a support without the aid of separate attaching members such as screws, bolts and rivets; and to provide a lamp mounting of improved construction in which the joint between the mounting and a support is completely obscured from view when the lamp is installed.

15 Further objects of the invention are to provide yielding means which bear between the lamp mounting and one side of its support for frictionally resisting turning of the lamp; to provide resilient means of this kind which 20 are placed under compression during installation of a lamp on a support and which remain under compression thereafter retaining the lamp in a position substantially normal to the surface of its support; and to provide 25 an improved lamp of this character which is of simple and inexpensive construction.

An illustrative embodiment of the invention is shown in the accompanying drawing, in which:

Fig. 1 is a central vertical section of the lamp and lamp mounting which embodies our invention.

Fig. 2 is a transverse vertical section taken on the line 2—2 of Fig. 1.

Fig. 3 is a central vertical section of a lamp and lamp mounting embodying a modified form of the invention.

Fig. 4 is a transverse vertical section taken on the line 4—4 of Fig. 3.

40 In the form shown in Figs. 1 and 2, our improved lamp mounting includes a cylindrical tubular member 1 comprising sheet metal material and having an unrestricted open end 2 for receiving the base portion 3 of an electric light bulb 4. The open end portion of the tube 1 is provided with diametrically opposite, L shaped slots 5 for receiving pins 6 on the periphery of the base 3 of the bulb.

Extending into the opposite ends of the 50 tube 1 is a contact member or bar 7 on the in-

ner end of which is mounted a disc 8 which is formed of insulating material, such as fiber, rubber or bakelite. Spaced sections of the left end portions of the tube 1 are bent inwardly so as to provide inwardly extending 55 radial flanges 9 and 10 on diametrically opposite sides of the tube. The flanges 9 and 10 form a seat against which a disc or washer 11, consisting of insulating material, is held by a helical spring 12 which bears between the 60 insulating discs 8 and 11 respectively. The disc 11 has a central aperture 13 which is larger in diameter than the rod 7 and which permits free and unobstructed movement of the rod and the disc 8 is held against displacement from the right end of the rod 7 by an enlarged head or contact element 14 which engages a contact element 15 of the light bulb and yieldably urges the latter outwardly so as to firmly hold the pins 6 of the light bulb 70 against the circumferential edge 16 of the L shaped slot 5.

Those portions of the sides of the tube 1 which are located between the extremities of the inwardly extending flanges 9 and 10, are bent outwardly so as to provide outwardly extending, radial lugs or bayonet joint elements 17 and 18 at diametrically opposite locations on the tube 1. Mounted on the outer periphery of the tube 1, between the opposite ends thereof, is an annular ring 19 having an inner cylindrical portion 20 in which the tube 1 is received, and an outwardly offset cylindrical portion 21 forming an annular channel around the periphery of 85 the tube. A yieldable cushion element 22 comprising resilient material, such as rubber, located in the channel formed by the ring 19, has an exposed end which extends through the open side of the channel and terminates in close proximity to the bayonet joint elements 17 and 18.

In installing a lamp and mounting of this kind on a support 23, such as an instrument board of a vehicle or a panel of a radio, the support is provided with a circular opening 24 of a diameter slightly larger than the outer diameter of the tube 1 and having communicating radial slots 25 for receiving the lugs 17 and 18 of the tube. The left 100

end of the tube 1 and the lugs 17 and 18 are inserted through the opening 24 and slots 25, respectively and the tube is then rotated through substantially 90° so as to move the lugs out of registration with the slots 25. As the exposed end of the yieldable member 22 is normally spaced from the lugs 17 and 18 an amount less than the thickness of the support 23, it is necessary to 10 press this yieldable element in order to move the lugs beyond the inner surface 26 of the support so as to permit the tube 1 to be rotated to a locked position. This compression of the yieldable member 22 causes the 15 support to be clamped between the lugs 17 and 18 and the exposed end of the yieldable element. Unintentional rotation of the bulb from its locked position is frictionally prevented by the exposed end of the yieldable 20 member 22 which bears upon the outer surface 27 of the support.

The entire mounting including the tube 1, bulb 4, ring 21 and yieldable element 22 is enclosed by a casing 28 having a flared end 25 portion 29 which is seated upon and piloted by the periphery of the offset cylindrical portion 21 of the ring 19. This casing has a slightly contour and it completely obstructs all elements of the lamp mounting from 30 view. The casing 28 has a light emitting slot 30 which is covered by a transparent member 31 located in the interior of the casing.

In the form shown in Figs. 3 and 4, the 35 lamp mounting includes a tubular member 1' having an open end 2' for receiving the base portion 3' of a light bulb 4'. The tube 1' has a pair of L shaped slots 5' for accommodating pins 6' on the outer periphery of 40 the base 3'. Extending into the other end of the tube 1' is a contact bar 7' having a head 14' on its inner end which engages the contact element 15' of the light bulb. The bar 7' is urged inwardly by a spring 12' 45 which bears between an insulating disc 8' mounted on the inner end of the rod 7' and an insulating disc 11' which is seated against the inwardly extending flanges 10' on the opposite sides of the left end portion of the 50 tube 1'.

Formed on the left end of the tube 1', as viewed in Fig. 3, are diametrically opposite, outwardly extending radial lugs 17' and 18' which serve as bayonet joint elements and 55 which extend through slots in a support 23' that communicate with a circular opening 24' of the support. A ring 19' having an inner cylindrical portion 20' in which the tube 1' is received and an offset cylindrical portion 21', is welded or otherwise secured to the outer periphery of the tube 1 at 32. The offset cylindrical portion 21' of the ring 19' has an inwardly extending flange 33 from which arms 34 are struck out. These arms extend 60 65 outwardly from the flange 33 to within close

proximity of the lugs 17' and 18'. When the flanged end of the tube 1 is inserted through the opening 24' of the support 23', the arms 34 resiliently bear upon the outer surface 27' of the support and firmly hold the lugs 17' and 18' against the inner surface 26' of the support. These arms frictionally resist unintentional turning of the tube 1' from its locked position and they hold the lamp mounting substantially normal to the support. 70 75

The lamp mounting shown in Figs. 3 and 4 is also provided with a casing 28' having a flared portion 29' which is seated upon the outer periphery of the offset cylindrical part 21' of the ring 19'. Formed in the casing 28' is a light emitting slot 30' which is covered by a transparent element 31' located in the casing. 80

A lamp of either of the above constructions may be conveniently mounted on a support by simply pressing the left end portion of the tube through an aperture in the support against the resistance of the yieldable elements and then turning the tube until the lugs thereof are out of registration with the slots of the support in which they are received during insertion of the mounting and the lamp may be as easily removed from the support by turning the tube until the lugs thereof register with their slots. 85 90 95

Although but several specific embodiments of this invention have herein been shown and described, it will be understood that various changes in the size, shape and arrangement of parts may be made without departing from the spirit of our invention and it is not our intention to limit its scope other than by the terms of the appended claims. 100 105

What we claim is:

1. A lamp mounting including a member having an irregular shaped base portion on one end including projecting elements for insertion through a correspondingly shaped opening in a support and having a bulb receiving recess at its opposite end, said base end portion being insertable through said opening from the side of said support on which the bulb receiving end of said member is desired, and being movable in said opening for placing the corresponding portion of said base portion and opening in misalignment after insertion of said base portion into said opening, and a rubber cushion on said member engageable with said support and located between the side thereof and the bulb receiving end of said member for yieldably resisting insertion of said base portion and frictionally resisting turning of said member. 110 115 120 125

2. A lamp mounting including a tubular member, bayonet joint elements extending outwardly from the periphery of said tubular member, a substantially rigid retainer surrounding intermediate portions of said tubu- 130

- lar member having a radially extending yieldable stop mounted in said retainer having an extremity in registering spaced relation to said bayonet joint elements and providing a 5 constricted groove adjacent the latter for receiving the thickness of a support, said stop including a yieldable non-metallic composition and being adapted to resiliently urge the joint elements against one side of the support and to frictionally resist turning of said member relative to said support, and a casing 10 removably mounted on the exterior of said retainer and surrounding said tubular member.
- 15 3. A lamp including a tubular member, flanges extending outwardly from the periphery of said tubular member for engaging one side of a support, an annular member having a wall substantially concentric with the latter, yieldable means between said annular member and said flanges for resiliently bearing upon the other side of a support, a bulb mounted in said tubular member, and a removable casing surrounding said bulb and 20 tubular member and seated upon the concentric wall of said annular member. 85
- 25 4. A lamp including a tubular member, flanges extending outwardly from the periphery of said tubular member for engaging one side of a support, an annular member rigidly mounted on said tubular member having a wall substantially concentric with the latter and having a recess therein, a rubber cushion in said recess having an exposed extremity 30 located between said annular member and said flanges for resiliently bearing upon the other side of a support, a bulb mounted in said tubular member, and a removable casing surrounding said bulb and tubular member and seated upon the concentric wall of 35 said annular member. 90
- 40 5. A lamp including a tubular member, flanges extending outwardly from the periphery of said tubular member for engaging one side of a support, an annular member rigidly mounted on said tubular member having a wall substantially concentric with the latter, integral resilient arms extending outwardly 45 from said annular member for resiliently bearing upon the other side of said support, a bulb mounted in said tubular member, and a removable casing surrounding said bulb and tubular member and seated upon the concentric wall of 50 said annular member. 100
- 55 6. A lamp including a tubular member, spaced inwardly extending flanges on one end portion of said tubular member, spaced outwardly extending flanges on the same end of said tubular member for engaging one side 60 of an instrument board, a light bulb in the other end of said tubular member including a base portion having protruding pins and an electrical terminal, the latter end of said tubular member being slotted for receiving 65 said pins, an electrical contact member ex- 105
- tending into the flanged end of said tubular member, means bearing between said contact member and said inwardly extending flanges for urging said contact member against said terminal, a ring rigidly mounted on the periphery of said tubular member having an offset cylindrical portion concentric with the tubular member, yieldable means held by said ring in close proximity to said outwardly extending flanges for engaging the 70 other side of said instrument board, and a casing removably seated on the offset cylindrical portion of said ring and enclosing said tubular member and light bulb. 75
